(Cl. D85—2)

To all whom it may concern:

Be it known that I, Theo R. Cotterell, a citizen of the United States and a resident of Huntington Park, county of Los Angeles, and State of California, have invented a new, original, and ornamental Design for a Figure Ash Tray or Similar Article, of which the following is a specification, reference being had to the accompanying drawing, forming part thereof.

Fig. 1 is a side elevational view of a figure ash tray or similar article, showing my new design;

Fig. 2 is a front elevational view thereof;

Fig. 3 is a rear elevational view thereof; and

Fig. 4 is a top plan view of the bottom portion thereof, with the cover removed and omitted for convenience of illustration.

I claim:

The ornamental design for a figure ash tray or similar article, as shown and described.
